PACKLESS EJECTOR FLUSH VALVE

Walter C. Weber, Aurora, Ill.

Application January 11, 1936, Serial No. 58,742

9 Claims. (Cl. 4—44)

This invention relates to a packless ejector flush valve.

An object of this invention is to eliminate all packings on the flush valve of flush tanks, thereby 5 eliminating the nuisance and expense of leaks and also the expense of repairs, such as replacing worn or faulty flush packings and also re-pairing ball cock seats which are cut due to leaky flush valve packings.

10 Another object of this invention is the provision of novel means for preventing water in the flush tank from being syphoned back into the water system through the ball cock, in the event the water is shut off and drained for repairs, etc., 15 thus preventing the slime and settling in the tank from being drawn back into the water system.

A still further object is the provision of simple 20 and efficient means in the construction of a flush valve mechanism, wherein a syphonic action, an injector action and a mechanical action is involved.

With the foregoing and other objects in view, 25 my invention comprises certain novel constructions, combinations and arrangements of parts as will be hereinafter fully described, illustrated in the accompanying drawing, and more particularly pointed out in the appended claims.

In the drawing:

30 Figure 1 is a view partly in side elevation and partly in vertical section of an apparatus constructed in accordance with the present invention, while

Figure 2 is a top plan view of the same.

35 Figure 3 is an enlarged sectional view taken on line 3—3, Figure 2 and looking in the direction of the arrow.

Figure 4 is a top plan view of the structure 40 illustrated in Figure 3.

Figure 5 is a perspective view of the cam device. 45 Figure 6 is a view partly in plan and partly in section taken on line 6—6, Figure 2.

It is to be understood, from the scope of the 50 following claims, that my broad principle may be reduced to practice in a number of modifications, and, therefore, I have illustrated in the accompanying drawing, one and the preferred embodiment in which 1 designates a tank into which extends in any suitable manner the inlet pipe 2. The tank 1 is also provided with and 55 suitably supports an outlet pipe 3, which will be hereinafter more specifically described.

Upon the upper end of the inlet pipe 2 (Fig. 3) 60 is detachably mounted a cap 4. The cap 4 is provided with a valve seat 5. A float valve casing 6 is threaded upon cap 4 against the annular flange 7. The casing 6 is provided with an integral horizontal ball valve casing 8. A bracket 9 is provided with a base 10 and an upstanding 65 arm 11 at one side and at its opposite side with

an upstanding arm 12. The base 10 constitutes a cover for the top of valve casing 6, the valve casing 6 and base 10 being detachably secured together by screws 13. Within valve casing 6 is mounted a float valve comprising body 14 that has an upstanding externally threaded stem 15 to which is detachably secured cap 16. This cap 16 extends through an aperture 17 of the base 10 for the purpose hereinafter described. A sleeve 18 is provided with a lower inwardly-extending flange 19; this sleeve 18 being screw threaded on the body 14. This sleeve 18 supports a disc 20 that normally engages the valve seat 5. An inverted cup-shape washer 21 is mounted on the body, between its upper end and 10 cap 16. By reason of this cup-shape washer 21, the water under pressure in pipe 2 will cause the valve to be raised quickly upon the device being manually operated as hereinafter described. 20

At opposite sides of the cover-like base 10 (Fig. 4) is a pair of upwardly-extending guides 22. A cam device 23 (Fig. 5) is movably mounted within these guides 22. This cam device comprises a central body 24 which is provided with parallel flat sides 25. Extending from opposite ends of body 24 are stub shafts 26. At the outer end of each shaft 26 is a disc 27. Extending horizontally from one disc 27 is an apertured lug 28. The shafts 26 are positioned between guides 22, 25 as shown by dotted lines in Fig. 4. The discs 27 serve to keep the cam device in position, against lateral displacement. 30

A compound lever 29, comprising link 30 and link 31, is employed. One end of link 30 is pivotally mounted at 32 upon the upstanding arm 11, with its other end pivotally connected at 33 to the upper end of link 31. A rod 34 is pivotally mounted at 35 upon the upstanding arm 12, and the rod is suitably connected at 36 to the lower end of link 31. An ordinary ball-like hollow float 37 is suitably fastened to the outer end of rod 34. An adjusting screw 38 extends through link 30 with its head 39 normally bearing against the cam device 23. A locking nut 40 is on the 40 threaded screw 38 against the link 30. 45

The ball valve casing 8 is provided with an internally threaded sleeve 41 into which is threaded the inlet end of jet connecting tube 42. Within casing 8 is formed a valve seat 43, which may be 50 engaged by ball valve 44. Pressure regulating screw 45 is threaded through the outer end of valve casing 8 and normally engages at its inner end ball valve 44. This valve closes against seat 43 to prevent any undesirable action by a back 55 flow through tube 42, to prevent sediment or slime in tank 1 from entering the valve casings.

The jet connecting tube 42 extends at its outer end under the syphon hood 46. This tube 42 is provided with a discharge aperture 47 (Fig. 6). 60

A valve sleeve 48 rotatably surrounds the outer end of tube 42 and is provided with an elongated discharge slot 49. An operating arm 50 extends downwardly from valve sleeve 48. On the lower 5 end of arm 50 is a weight 51. A horizontal rod 52 is mounted on the upper portion of the tank, with its inner end detachably connected at 53 to the apertured lug 28 (Fig. 2). The rod 52 extends at its outer end beyond the outer face of tank 1, and suitably secured to said extended end is a depending handle 54. This handle acts as a weight, together with weight 51, to return the mechanism to its normal closed or set position after it has been operated. A rod 55 is connected 10 at its lower end to arm 50 and at its upper end it is pivotally connected at 56 (Fig. 2) to rod 52. It will, therefore, be seen that when handle 54 is turned a quarter way around in either direction, not only will cam valve 23 be released, 15 allowing the float valve to rise, but sleeve 48 will be synchronously rotated to cause slot 49 to register with aperture 47 allowing discharge of water under pressure into the syphon hood 46. The upper end of the outlet pipe 3 is preferably 20 enlarged in diameter from point 57, for the purpose hereinafter described. In other words, the upper end of the outlet pipe is larger than the lower end, said pipe being reduced at 57. The 25 syphon hood is preferably attached at 58, 59 to the side of the outlet pipe 3, the outlet pipe being bevelled at 59 for allowing ready discharge of the water from the tank and jet device into the discharge pipe.

A refill tube 60 is required by sanitary laws of 30 various cities as an after-fill on water closets or other receptacles which have a tendency to lose their water seal when syphoned empty and is not an essential part of the flush valve except as required for refilling the water seal in a trap, as in water closet bowls, etc. Packing nut 61 permits of making an air tight joint at the junction between the refill tube 60 and syphon hood 46. The outer end of tube 60 opens into the valve casing 6 (Fig. 3) contiguous to the float valve therein, while the inner end discharges downwardly into the outlet pipe 3, as clearly shown in Fig. 1.

The hereinbefore referred ball valve 44 accurately regulates the pressure of the jet because it is held the correct distance from seat 43 by said regulating screw 45. This ball valve 44 being free, is drawn against the seat 43 when a current of water flows back into the ball casing 8, due to the water being shut off and drained, thus preventing the contents of the flush tank from being syphoned back into the water system.

An advantage of reducing the outlet pipe at 51 is that it facilitates starting of the syphonic action. The reduction at 57 assists in causing the syphon action to respond quicker than when the tube is the same diameter all the way.

The water in tank 1 is normally of the same height inside of the syphon hood as it is outside, in the tank as a whole.

The jet of water that is released into the syphon hood 46 through the jet valve constituted by the apertured end of tube 42 and sleeve valve 48 (Fig. 6) actuates the syphon to cause it to function as an ejector as well as a syphon, the jet supplying additional impetus required to expel the contents of the flush tank for flushing purposes through the syphon.

When the distance in height between the inlet 75 and outlet tubes of the syphon is a few feet or

more, the velocity at the outlet of the syphon is sufficient for flushing purposes. However, where this distance is only a few inches, as in the case in low tank closets, additional impetus must be supplied, this being accomplished by the injection 5 of a small jet into the syphon inlet, constituted within the syphon hood 46, causing the syphon to function as an ejector. The jet at 47, therefore, has several purposes: first, to actuate the syphon within hood 46; second, to increase the 10 velocity of the water at the outlet 59 of the structure, causing it to function as an ejector, and third, to refill the flush tank 1.

When the device is operated by swinging handle 54 either to the right or left a quarter of a 15 turn, not only is the cam device 23 rotated to allow the float valve to rise against one of the flat faces 25, but this action turns the valve sleeve 48 so that slot 49 is over jet aperture 47, thereby permitting the jet of water to flow upward into 20 and through the syphon hood 46. Slot 49 is long enough to permit the sleeve 48 to be gradually rotated, to return to its righted position (Fig. 6) without obstructing the full opening condition of aperture 47, until cam device 23 swings into 25 its righted position (Fig. 3) which takes place when the float 37 has lowered sufficiently to permit sufficient clearance between the cam device 23 and cam adjusting screw 38. The water pressure exerted on the cup washer 21 holds 30 the cam device 23 in the open position, thereby holding the "jet converter" or sleeve 48 in the open position until the float 37 lowers in the flush tank, due to the water being drained out. Since 35 the body 24 of the cam device 23 is of an oval shape, the same will gradually turn as float 37 lowers, and eventually return to the righted position due to the clearance being increased between the cam adjusting screw 38 and the cap 16, which can only rise a given distance due to 40 the construction as hereinbefore described. As hereinbefore stated, the cam device 23 is caused to return to the righted or normal position by reason of the weight of handle 1 and weight 51. After the float 37 has travelled down, due to 45 the water in flush tank 1 lowering sufficiently to allow the cam device 23 to right itself completely, the slot 49 in valve sleeve 48 has also passed entirely over the aperture 47, thereby intercepting 50 the jet of water in its upward direction through the "syphon" or hood 46 and allows the jet to flow directly into the flush tank 1 to refill the same. The syphonic action of the flush valve still persists after the jet has been diverted into the tank, until it has lowered the water in the 55 tank to a level corresponding to the bottom of the inlet or syphon hood 46, or to a level of any opening in the hood 46 which will cause air to enter the hood, thereby breaking the syphonic action of the flush valve. The water entering 60 the tank 1 through the slot 49 and aperture 47, refills the tank and is gradually shut off by the action of the cam device and the float 37, whereby the water is eventually stopped from flowing into the tank 1 when the float 37 exerts sufficient 65 pressure by means of the compound lever 29 on the cam device and float valve within casing 6 to cause the float valve to be tightly seated at 5.

While I have described the preferred embodiment of my invention and illustrated the same 70 in the accompanying drawing, certain minor changes or alterations may appear to one skilled in the art to which this invention relates during the extensive manufacture of the same, and I, therefore, reserve the right to make such changes 75

or alterations as shall fairly fall within the scope of the present invention.

Further, in the following claims, I use the term "injector" in a broad sense, meaning an "ejector" 5 when applied to the siphon hood or arrangements for quickly and efficiently removing the water from tank 1 for flushing action.

What I claim is:

1. In an apparatus of the class described, the 10 combination with a flush tank, of an outlet pipe extending into said tank and being reduced within the tank, a siphon hood over said outlet pipe, means attaching said hood to one side of said outlet pipe, said outlet pipe being bevelled at 15 its upper end, and means for supplying a jet of water into said siphon hood or into said tank.

2. In an apparatus of the class described, the 20 combination with a flush tank, of an outlet pipe extending into said tank, a siphon hood over the inner end of said outlet pipe, supply means including a jet valve under said siphon hood, said jet valve comprising an apertured tube, a rotatable sleeve provided with a slot on said tube, and said slot being adapted to register with the 25 aperture in said tube.

3. In an apparatus of the class described, the 30 combination with a flush tank, of an outlet tube extending into said tank, an inlet tube extending into said tank, a valve casing on said inlet tube, a float valve in said casing, said float valve comprising a body provided with upwardly extending threaded stem, a threaded sleeve provided with a flange on the lower part of said body, a disc engaging the lower face of said 35 body and supported against said flange, an inverted cup washer on said body and around said threaded stem, a cap on said threaded stem against said cup washer, manually operated and float operated means engaging said cap for holding the float valve in a closed position or permitting the same to move to an open position, a hood on said outlet tube, and means connected to said float valve casing and being capable of discharging water into said hood or directly into 45 said tank.

4. In an apparatus of the class described, the 50 combination with a flush tank, of an outlet pipe extending into said tank, an inlet pipe extending into said tank, said inlet pipe provided with a float valve at its inner end, a rotatable cam device co-operating with said float valve, said rotatable cam device comprising a body provided with parallel flat sides, said body provided at its ends with stub shafts, each shaft provided 55 on its outer end with a disc, one of said discs provided with an apertured lug, manually operated handle means connected to said apertured lug. A float means in said tank and provided with lever means co-operating with said cam device, and a valve-controlled water discharge means connected to said float valve.

5. In an apparatus of the class described, the 60 combination with a flush tank, of an outlet pipe extending into said tank, an inlet pipe extending into said tank and provided with a float valve at its inner end within the tank, rotatable cam means co-operating with said float valve for normally holding it in a closed position, a compound lever mounted above and on 65 said float valve and co-operating with said rotatable cam means, said compound lever pro-

vided with an adjusting screw having a head bearing against said cam means, a float in said tank and connected to said compound lever, a siphon hood over said outlet pipe, and means connected to said float valve and being adapted to discharge water into said hood or directly into said tank. 5

6. In an apparatus of the class described, the 10 combination with a flush tank, of an outlet pipe extending into said tank, a hood around the inner end of said outlet pipe, an inlet pipe extending into said tank, said inlet pipe provided on its inner end with a float valve, a jet tube connected to said float valve, a jet valve under said hood and mounted on said jet tube, a cam 15 device supported by and cooperating with said float valve, an operating handle connected to said cam device, and means connecting said operating handle and said jet valve whereby when the operating handle is operated the float valve 20 will be released and the jet valve will be opened.

7. In an apparatus of the class described, the 25 combination with a flush tank, of an outlet pipe extending into said tank, a hood around the inner end of said outlet pipe, an inlet pipe extending into said tank, said inlet pipe provided with a float valve on its inner end, a jet tube connected to said float valve, a jet valve under said hood and mounted on said jet tube, said jet valve including a slotted sleeve and a depending arm, a weight on the lower end of said arm, a cam device supported by and cooperating with said float valve, an operating handle constituting a weight connected to said cam 30 device, and a rod pivotally connected at its lower 35 end to the arm of the jet valve and being pivotally connected to said operating handle.

8. In an apparatus of the class described, the 40 combination with a flush tank, of an outlet tube extending into said tank, an inlet tube extending into said tank, a float valve casing on the inner end of said inlet tube, a float valve in said casing, a bracket covering the upper end of said float valve casing, said float valve extending through a portion of said bracket, a rotatable 45 cam device slidably mounted on said bracket and engaging the extended portion of said float valve, said bracket device comprising upstanding arms, a compound lever pivotally mounted on said upstanding arms, a float within said tank 50 and connected to said compound lever, an adjustable screw carried by said compound lever and bearing against said cam device, and means for conveying water from said float valve to and discharging it either into said outlet pipe or directly into said tank. 55

9. In an apparatus of the class described, the 60 combination with a flush tank, of inlet and outlet pipes extending into said tank, a hood over said outlet tube, a float valve and a ball valve 65 casing integrally connected together and mounted on said inlet tube, a ball valve in said ball valve casing, a pressure regulating screw extending through one end of said ball valve casing and against said ball valve, manually operated means and float operated means cooperating with and controlling movement of said float valve, and means connected to said ball valve casing and being capable of discharging water into said hood or into said tank. 70

WALTER C. WEBER.
